UNITED STATES PATENT OFFICE

WARREN L. MARK, OF MILLERSBURG, PENNSYLVANIA

WHISK BROOM

Application filed March 18, 1930. Serial No. 436,834.

This invention relates to brooms and more particularly to whisk brooms.

The primary object of this invention is to provide an improved whisk broom construction wherein the handle is positioned in angular relation to the tufts of the broom.

Another object of this invention is to provide in a broom of this character a construction by means of which exceedingly long tufts 10 of fiber may be used, the fiber being so positioned upon the handle structure that it will not be readily withdrawn or loosened therefrom.

A further object of this invention is to provide a broom structure wherein the means for securing the tufts upon the handle may be extended or wound about the handle so as to provide a smooth handle of pleasing appearance.

The above and various other objects and advantages of this invention will in part be described in and in part be understood from the following detailed description of the present preferred embodiment, the same being 25 illustrated in the accompanying drawing wherein:—

Figure 1 is a detail side elevation partly in section of a device constructed according to the preferred embodiment of this invention; and

Figure 2 is a detail end elevation of the device.

Referring to the drawing wherein like numerals of reference designate corresponding parts throughout the several views, the numeral 10 designates an elongated member which is preferably circular in cross section and about which a plurality of tufts of broom fiber 11 are adapted to be mounted, the fiber 11 adjacent the forward end of the member 10 being extended substantially throughout the length of the pin or member 10 and positioned about the periphery thereof.

The tufts of fiber 11 positioned about the periphery of the body member 10 extend over the end of the body member and downwardly therefrom at substantially right angles thereto so as to provide a cushion or protecting portion for the outer end of the body member 10.

A plurality of relatively long tufts of fiber 12 are secured to the body member 10 and are positioned in alignment with the fiber 11 which extends about the periphery of the body 10, the fiber 12 comprising relatively long tufts which are looped as at 13 and firmly held against the periphery of the body member 10 by means of a wire or securing members 14.

One end of the securing member 14 may be 60 nailed or tacked onto the body member 10 adjacent the forward end thereof, and the wire then wound about the tufts of fiber 11 and extended into the looped portions 13 of the tufts 12 so as to provide the desired width of 65 broom structure upon the body member 10.

The wire 14 may be continued inwardly from the inner tuft 12 and wound about the body member 10 so as to provide a handle portion 15, the handle portion 15 being of any desired length and the inner end of the wire 14 may be secured as by a nail or the like 16 to the inner end portion of the body 10.

A cap 17 may be secured to the inner end 75 of the body member 10 and extend over the inner end portion of the wire 14 so as to provide a handle structure of relatively pleasing appearance, the cap member 17 being secured to the body member 10 by means of a nail or headed member 18.

A loop or ring member 19 may be loosely mounted in the cap 17 so as to permit hanging of the broom on a nail or the like. The tufts of fiber 11 and 12 are firmly held together by 85 means of a pair of saddle members 20 or the like, the saddle members 20 being of conventional construction in the form of a flexible cord or the like which is wound about the fibers 11 and 12 and extended from side to 90 side in the conventional manner for securing the saddle members.

When the whisk broom herein disclosed has been assembled, it will be obvious that an exceedingly convenient broom structure has been provided by means of which the bread crumbs or the like may be removed from tables, or the interior of motor vehicles may be readily cleaned, particularly the deep up- 95 holstery or the like which cannot be properly 100

cleaned by broom structures at present available.

It will, of course, be understood that various changes and modifications may be made in the details of construction and design of the above specifically described embodiment of the invention without departing from the spirit thereof, such changes and modifications being restricted only by the scope of the following claims.

What is claimed is:—

1. A broom of the character described comprising an elongated body member, a plurality of fiber tufts positioned about the periphery of said body member and extending over one end thereof, the extended portion of said tufts being positioned in angular relation to said body member, a plurality of looped fiber tufts, means for securing said first named and said looped fiber tufts to said body member, said looped tufts being positioned outside of said first named tufts and saddle means for holding said fiber tufts together.

2. A broom of the character described comprising an elongated body member, tufts of fiber positioned about the periphery of said annular member and extending over one end thereof, the extended portion of said tufts being positioned in angular relation to the body, a plurality of looped fiber members secured to said body rearwardly of the extended portion of said first tufts, means for securing said first and said second fiber members to said body member, said securing means being extended along said body member whereby to provide a handle structure, and a cap positioned on the opposite end of said body member and engaging about said handle portion.

3. A whisk broom of the character described comprising an elongated body member, fiber tufts positioned about the periphery of said body member and extending over one end thereof, said extended portion depending from said body member at substantially right angles thereto, a series of looped fiber tufts secured to said body rearwardly of the extended portion of said first tufts, means for securing said first mentioned fiber tufts and said series of tufts to said body member, saddle means for said fiber tufts, said securing means for said tufts being extended along said body member whereby to provide a handle portion outwardly of said tufts and at substantially right angles thereto.

4. A broom of the character described comprising a body member substantially circular in cross section, tufts of fiber positioned about said body member and extending inwardly of the outer end thereof and about the periphery of said body member, said tufts also extending over the outer end portion of said body member whereby to conceal the outer end of said body member, a series of looped fiber tufts secured to said body outside of said first tufts, a wire se-

cured at one end to said body adjacent the outer end portion thereof, said wire being wound about the body and said tufts of fiber, said wire also being wound through the looped portions of said series of looped fibers whereby to secure said fibers to said body member in dependent relation, said wire being wound about said body member inwardly from said looped fiber tufts whereby to provide a smooth handle structure, means for securing the opposite end of said wire on the inner end of said body, an apertured cap, means for securing said apertured cap on the inner end portion of said body, and a pair of saddle members adapted to hold said tufts of fiber together.

5. A whisk broom of the character described comprising a body member substantially circular in cross section, a plurality of fiber tufts positioned upon the periphery of said body member and extending outwardly therealong and outwardly from the outer end portion thereof, said latter extended portions being angularly inclined from the outer end of said body, a series of looped fiber tufts secured to said body outside of said first tufts, a wire secured at one end to said body member adjacent the outer end portion thereof, said wire being wound about said body and said first mentioned tufts of fiber, said wire being extended through the looped portions of said looped fibers whereby to firmly hold each of said tuft portions upon said body member and in angular relation thereto, said wire being wound about said body member from the innermost of said looped fiber tufts to a point adjacent the inner end portion of the body member whereby to provide a smooth metal handle portion, means for securing the opposite end of said wire to the body adjacent the inner end thereof, a plurality of saddle members secured to said tufts of fiber whereby to firmly hold said tufts together, an apertured cap positioned on the inner end of said body member and about the inner end portion of said wire, a headed member adapted to firmly hold said cap on said body, and a looped member loosely carried by said cap.

In testimony whereof I hereunto affix my signature.

WARREN L. MARK.
